DESIGN FOR A SCARF OR SIMILAR ARTICLE

Sydelle Rosen, New York, N. Y.

Application September 30, 1937, Serial No. 71,879

Term of patent 3½ years

To all whom it may concern:

Be it known that I, Sydelle Rosen, a citizen of the United States of America, residing in New York city, in the Borough of Manhattan, county and State of New York, have invented a new, original, and ornamental Design for a Scarf or Similar Article, of which the following is a specification, reference being had to the accompanying drawing, forming part thereof, wherein,

The figure is a plan view of a scarf or similar article showing my new design.

In the drawing, the scarf has its center areas sectioned off longitudinally and transversely to reduce the size of the textile unit, the exact dimensions of which being 40 inches wide and 4 yards long.

The design comprises a scarf of rectangular configuration, having a border surrounding a field, composed of elements of diagonally arranged blocks in groups of three of contrasting colors, the groups being arranged in vertical and horizontal lines as shown.

I claim:

The ornamental design for a scarf or similar article, substantially as shown, and described.

SYDELLE ROSEN.
